UNITED STATES PATENT OFFICE

163,740

SPECTACLE FRAME

Frank A. Blasi, Newark, N. J.

Application April 11, 1951, Serial No. 14,798

Term of patent 14 years

(Cl. D57—1)

To all whom it may concern:

Be it known that I, Frank A. Blasi, a citizen of the United States of America and residing at 31-33 Governor Street, Newark, New Jersey, county of Essex, have invented a new, original, and ornamental Design for a Spectacle Frame, of which the following is a specification, reference being had to the accompanying drawing, forming a part thereof.

Fig. 1 is a front elevational view of a spectacle frame, showing my new design; and

Fig. 2 is an enlarged perspective view of the ornamentation shown in full lines in Fig. 1, for the purpose of bringing out more clearly the details thereof.

The essential features of my design are shown in full lines.

I claim:

The ornamental design for a spectacle frame, substantially as shown and described.

FRANK A. BLASI.
